BOBBIN CHANGING LOOM

Carl D. Brown, Hopedale, Mass., assignor to
Draper Corporation, Hopedale, Mass., a cor-
poration of Maine

Application November 3, 1937, Serial No. 172,554

8 Claims. (Cl. 139—251)

The present invention pertains to the filling replenishing mechanism of automatic bobbin changing looms and more particularly to bobbin holding means thereof.

Automatic looms of the type to which my invention applies commonly include a hopper arranged to successively present the bobbins in position to be transferred to a shuttle, and a trans-
ferrer which periodically transfers a fresh bob-
bin to the shuttle and ejects the spent bobbin
therefrom. Such looms may also include a filling
end parting mechanism which is normally in an inoperative position but which is moved to parting position before transfer and returned
to inoperative position after the transfer is completed. The construction of the hopper is such that the bobbin therein which is in position to be transferred is apt to turn on its own axis, which turning frequently results in breakage of
the filling end leading from the bobbin.

It has been proposed heretofore to prevent the aforementioned turning of bobbins in the hopper by providing a bobbin supporting or holding member for frictionally engaging the bobbin
which is in position to be transferred. Such sup-
porting members as heretofore constructed have been movably mounted on some stationary sup-
port and moved out of bobbin supporting position by the trans-
ferrer. These prior supporting
members are apt to interfere with transfer of the bobbin, because the construction is such that the supporting member must move a con-
siderable distance to get out of the path of the bobbin being transferred and does not start such movement until the trans-
ferrer starts its operative stroke.

A principal object of the present invention is to provide a filling replenishing mechanism including a trans-
ferrer as aforesaid, a bobbin sup-
porting member which is movably mounted on the trans-
ferrer whereby such member is not re-
quired to move any very substantial distance to clear the path of the bobbin being transferred, and means for moving said member away from
said path before transfer and returning it to operative position is completed.

A further object of the invention is to provide filling replenishing mechanism including a hopper, trans-
ferrer and filling end parting mecha-
nism constructed and operating as aforesaid, and a bobbin supporting member which is moved out of bobbin engaging position by means oper-
ated by said parting mechanism, whereby such movement is effected before the trans-
ferrer starts its operative movement.

The foregoing and other objects of the invention are accomplished in the construction illus-
trated on the accompanying drawing, of which:

Fig. 1 is a view in cross-section showing part of an automatic bobbin changing loom having 5
the preferred embodiment of my invention applied thereto;

Fig. 2 is a similar view illustrating operation of the parts at the time of transfer; and

Fig. 3 is a horizontal sectional view of the 10
same.

The drawing shows only part of an automatic bobbin changing loom having the preferred em-
bodiment of my invention applied thereto, other parts and mechanisms not shown being of any 15
usual construction not of the present invention. Such loom includes the usual lay beam 1 which carries at its right hand end a shuttle box 2 and which reciprocates toward and from the front of the loom, the front of the loom being toward 20
the left on Figs. 1 and 2. A suitable hopper such as the usual rotary hopper 3 is arranged to carry a reserve supply of bobbins 4, 4 and to success-
ively present the bobbins in position to be trans-
ferred to the loom shuttle 5. The bobbin 4¹, Fig. 25
1, is in transferring position, which is directly over the shuttle box 2 when the lay beam 1 is at or near its forwardmost position.

The shuttle 5 is picked along the lay beam 1, from side to side of the loom, by any usual pick- 30
ing means. When the filling supply in the shuttle becomes substantially exhausted the usual de-
tecting means (not shown) initiates operation of the filling replenishing mechanism to thereby effect the transfer of bobbin 4¹ to the shuttle. 35
The filling replenishing mechanism includes a trans-
ferrer which has a periodic transferring move-
ment, i. e., the trans-
ferrer has an operative move-
ment only at the end of each period de-
fined by substantial exhaustion of the filling 40
supply in the shuttle. The particular trans-
ferrer 6 shown is normally stationary in the position
illustrated by Fig. 1.

The trans-
ferrer 6 is pivotally mounted on a
stud 7 which is fixed in hopper stand 8. The 45
trans-
ferrer includes a rearwardly extending arm
having a bobbin-engaging head at its rearward
end. Such head may include a depending por-
tion 9 for engaging the butt of the bobbin and a laterally extending rod 10 having a depending 50
fork 11 for engaging the filling supply on the
bobbin. The portion 9 and fork 11 are normally
positioned directly over the bobbin 4¹. The
trans-
ferrer 6 also includes a depending arm 12
having a latch 13 pivoted thereto. The latch 55

13 normally hangs down as on Fig. 1 but upon call for filling replenishment is moved upwardly into the path of a bunter 14 on the lay beam 1. Then, when the lay beam next moves forwardly 5 the bunter 14 engages latch 13 and swings the transferrer head downwardly to transfer the bobbin 4¹ to the shuttle, Fig. 2. The transferrer head is moved upwardly, by spring 15, as the lay beam recedes, and the hopper 3 simultaneously 10 moves the next bobbin 4 into transferring position.

The loom shown also includes filling end parting mechanism for parting and clamping the outgoing filling end at the time of transfer. The 15 parting mechanism may include parting blades 16 which are mounted on a carrier 17. The carrier 17 is slidably supported on a fixed guide 18 for movement rearwardly to operative or parting position and forwardly to inoperative position. An 20 actuator 19 is pivoted on the stud 7. This actuator swings rearwardly, to move the parter carrier and blades rearwardly, at the same time that latch 13 is moved upwardly, which is less than one pick prior to actual transfer. The actuator 25 swings forwardly, to move the parter blades to inoperative position, immediately after the transferring operation is completed. This parting mechanism is not, per se, of the present invention, a more complete disclosure being found in 30 patent to Burdett, No. 1,833,532, granted Oct. 18, 1932.

It is the bobbin 4¹ in transferring position that tends to turn on its own axis in the hopper. The present invention provides, in combination with 35 parts such as those above described, means for effectively holding or supporting the bobbin against turning. The preferred embodiment of such supporting means includes a bobbin supporting member in the form of a lever 20. In 40 accordance with the invention the lever 20 is movably mounted on the transferrer, it being preferably pivoted on the rod 10 of the transferrer head. A depending arm 21 of the lever 20 has a friction head 22. A spring 23 serves to bias 45 the lever counter-clockwise, Fig. 1, and thus holds the head 22 in frictional engagement with the bobbin 4¹. The friction head 22 bears upwardly and rearwardly against the bobbin and the latter is prevented from turning both because it is 50 supported in proper position in the hopper and because it is frictionally engaged by the head 22.

Since the bobbin supporting member 20 is mounted on the transferrer head and therefore moves up and down with the transferrer, only a 55 slight pivotal movement of the member on the rod 10 will move the head 22 out of the path which bobbin 4¹ follows in being transferred to the shuttle. The invention further provides novel means for moving a bobbin supporting member, 60 such as member 20, to and from bobbin engaging position.

In the preferred embodiment, the upper end of member 20 is provided with a stud 24 engaging in a slot 25 in the rearward end of a connecting link 26. The forward end of the link 26 is pivoted at 27 to a stand 28 on the actuator 19. The construction is such that when the actuator 19 is forward and latch 13 is down the friction head 22 is in supporting engagement with the bobbin 4¹. Upon call for replenishment of the filling supply, the actuator 19 swings rearwardly 70 to move the parting blades 16 to operative position. Simultaneously with said movement of the parting blades, the connecting link 26 is operated by the actuator 19 to pivot the lever 20 clockwise 75

on rod 10 and thereby move the head 22 forwardly out of engagement with the bobbin 4¹.

The aforementioned movement of head 22 out of bobbin supporting position occurs substantially in advance of engagement of latch 13 by bunter 5 14. Thus, the bobbin supporting member is moved out of the path of bobbin 4¹ before the transferring movement of transferrer 6 is started. The actuator 19 remains in its rearward position and holds the lever 20 out of bobbin supporting 10 position during operation of the transferrer. Immediately after the transferrer has completed its downward and upward movement and the hopper has presented another bobbin in transferring position, the actuator 19 returns to its forward 15 position. This forward movement of the actuator is accompanied by return of the lever 20 to bobbin supporting position.

The embodiment herein disclosed is simple, yet 20 very effective in preventing bobbins from turning in the hopper. Furthermore, the bobbin supporting member and its supporting and operating means are so arranged that the device will not cause improper transfers by obstructing the bobbin which is being transferred to the shuttle. 25

Having fully disclosed the preferred embodiment of my invention, I claim:

1. In a filling replenishing mechanism for automatic bobbin changing looms, the combination of 30 a transferrer, a bobbin supporting device movably mounted on said transferrer for movement into and out of bobbin supporting position, and means for moving said device out of said position prior to operative movement of said transferrer and returning said device to said position after said movement of said transferrer is completed.

2. In a filling replenishing mechanism for automatic bobbin changing looms, the combination of 40 a normally stationary transferrer having a periodic bobbin transferring movement, a bobbin supporting member pivotally mounted on said transferrer for movement into and out of bobbin supporting position, and means for moving said member out of said position prior to movement of said transferrer and returning said member to bobbin supporting position immediately after 45 said movement of said transferrer is completed.

3. In a filling replenishing mechanism for automatic bobbin changing looms, the combination of 50 a rotary hopper arranged to successively present bobbins in position to be transferred to a shuttle, a normally stationary transferrer having a periodic bobbin transferring movement, a bobbin supporting member pivotally mounted on said transferrer for movement into and out of supporting 55 engagement with the bobbin in transferring position in said hopper, and means for moving said member out of engagement with said bobbin prior to movement of said transferrer and returning said member to bobbin supporting position immediately after said movement of said transferrer is completed.

4. In a bobbin changing loom, the combination of 60 a hopper arranged to successively present bobbins in position to be transferred to a shuttle, a bobbin changing mechanism including a trans- 65 ferrer, filling end parting mechanism moving to operative position prior to transfer and away from said position after transfer, a bobbin supporting member, and means operated by said 70 parting mechanism for moving said member into and out of supporting engagement with the bobbin in transferring position in said hopper.

5. In a bobbin changing loom, the combination of 75 a hopper arranged to successively present bob-

bins in position to be transferred to a shuttle, bobbin changing mechanism including a trans-
ferrer, filling end parting mechanism including
parting blades and an actuator for moving said
blades to parting position prior to transfer and
away from said position immediately after trans-
fer, a bobbin supporting member normally in
engagement with the bobbin in transferring
position in said hopper, and means operated by
said actuator for moving said member out of en-
gagement with said bobbin simultaneously with
movement of said blades to parting position.

6. In a bobbin changing loom, the combination
of a rotary hopper arranged to successively pre-
sent bobbins in position to be transferred to a shuttle, bobbin changing mechanism including a
normally stationary transerrer having a periodic
transferring movement, filling end parting mech-
anism moving to operative position prior to trans-
ferring movement of said transerrer and away
from said position after transfer is completed,
a bobbin supporting member pivotally mounted
for movement into and out of engagement with
the bobbin in transferring position in said hop-
per, and means operated by said parting mech-
anism for moving said member out of engagement
with said bobbin simultaneously with movement
of said parting mechanism to operative position,
said means returning said member to bobbin
supporting position simultaneously with move-
ment of said parting mechanism away from op-
erative position.

7. In a bobbin changing loom, the combination
of a hopper arranged to successively present bob-

bins in position to be transferred to a shuttle, bobbin changing mechanism including a trans-
ferrer, a bobbin supporting member movably
mounted on said transerrer and arranged to
support the bobbin in transferring position in
said hopper, filling end parting mechanism moving
to operative position prior to transfer and
away from said position immediately after trans-
fer, and connections between said parting mech-
anism and said member constructed and arranged
to move said member out of and into bobbin
supporting position as said parting mechanism
moves respectively toward and away from its
operative position.

8. In a bobbin changing loom, the combination
of a hopper arranged to successively present bob-
bins in position to be transferred to a shuttle, bobbin changing mechanism including a normally
stationary transerrer having a periodic bobbin
transferring movement, a lever pivotally mounted
on said transerrer and having an arm support-
ing the bobbin in transferring position in said
hopper, filling end parting mechanism including
parting blades and an actuator moving said blades
to parting position prior to movement of said
transerrer and away from said position after
movement of said transerrer is completed, and
a link connecting said actuator with said lever
for moving said arm away from and toward bob-
bin supporting position as said parting blades
are moved respectively toward and away from
operative position.

CARL D. BROWN.
